UNITED STATES PATENT OFFICE.

WALTER E. KEMP, OF SAULT STE. MARIE, MICHIGAN, ASSIGNEE OF ONE-HALF TO
JAMES H. ELLIOTT, OF SAULT STE. MARIE, MICHIGAN.

WASHING-MACHINE.

1,097,445.

Specification of Letters Patent.

Patented May 19, 1914.

Application filed April 2, 1913. Serial No. 758,416.

To all whom it may concern:

Be it known that I, WALTER E. KEMP, a citizen of the United States, residing at Sault Ste. Marie, in the county of Chippewa and State of Michigan, have invented new and useful Improvements in Washing-Machines, of which the following is a specification.

This invention relates to washing apparatus, and particularly to pounders which when operated tend to induce suction immediately above the clothes, so as to thoroughly agitate the water and draw the same through the clothes; and it has for its object the provision of a device of this character which will be provided with means for positively preventing the lateral scattering of the water during the pounding operation.

Another object of the invention is the provision of a soap box which will serve to hold the soap in a position to permit of its being properly immersed in the water during the pounding operation and which will be defined by a yieldable bottom member and the adjacent walls of the head of the device.

Another object of the invention is the provision of a soap box wherein a portion thereof is constructed with a view to facilitating the operation of applying the soap to the device.

Another object of the invention is the provision of means for maximizing the gripping contact of the device against the clothes whereby to permit the latter to be revolved effectually in the water during the pounding operation.

With these and other objects in view, the invention consists of certain novel features of construction, combination and arrangement of parts, as will be hereinafter described and claimed.

In the accompanying drawings:—Figure 1 is a side view of the device; Fig. 2 is a vertical longitudinal section therethrough; and Fig. 3 is a bottom plan view of the device.

The device comprises a conical pounding head 1 which is provided at its apex with a relatively long sleeve 2, in which is securely fitted the lower end of an operating handle 3. The head 1 is provided at its lower end with a reinforcing bead 4, in which is preferably arranged a strengthening wire 5.

The head 1 is provided preferably near its lower end with apertures 6, over which are

extended shields 7, the latter being soldered or otherwise suitably secured to the member 1 exteriorly thereof and arranged in spaced relation with the opening 6 and provided with relatively large open lower ends which are spaced from the lower edge of the head and which serve to collect the water and prevent the lateral scattering of the same during the pounding operation. Within the head 1 are arranged members 8, which are preferably of triangular configuration in transverse section and associated with the inner walls of the head, so as to define therewith pockets 9 of an upwardly restricted diameter. The lower edges of the members 8 are spaced from the lower end of the head 1, so as to permit of the effective purchase of the bead 4 against a mass of clothes, and to cause portions of the clothes to be properly forced or advanced into the pockets 9 to thereby cause the clothes to be given a circulatory movement when the handle 3 is partly revolved during the pounding operation. It is evident that under the force of the plunger against the clothes there will be sufficient accumulation of air beneath the clothes to effect a projection of portions of the clothes into the lower or large ends of the pockets. The members 8 are provided with right angularly disposed walls, whose longitudinal edges are preferably soldered to the inner walls of the head. The members 8 are disposed immediately behind the opening 6, as shown.

In order that a proper quantity of soap may be mixed with the water during the washing operation, I provide a tray 10 which directly underlies the apex of the conical head 1, it being relatively associated with the adjacent walls of the head, so as to form a soap box, in which small portions of soap may be arranged and confined under the action of the tray 10. The tray is preferably of rectangular configuration so that all of its edges are spaced from the adjacent inner walls of the head 1, whereby to permit the water as it leaves the soap to effectually pass back into the tub. The tray 10 is preferably foraminous, being made of sheet metal and provided with a plurality of apertures 11, as illustrated. With a view to preventing the soap from being accidentally displaced from the soap box I provide the tray 10 with flanges 12, which are adapted to overlap the sides of the soap to hold the lat-

- ter against slipping from the tray. The tray is provided at two corners with hinge springs 13, the terminals 14 of which being secured to the tray while the terminals 15 are secured to the inner walls of the head 1. Under the influence of the springs the tray is normally held in a horizontal position where it will operatively support the soap. The opposite end of the tray is preferably provided with a manipulating member 16, which may be grasped by the hand when it is desired to move the tray to a position to permit of the required application of soap to the device.
15. From the foregoing description, taken in connection with the accompanying drawings, the construction and operation of the invention will be readily understood without requiring a more extended explanation.
20. Various changes in the form, proportion and the minor details of construction may be resorted to without departing from the

principle or sacrificing any of the advantages of this invention, as claimed.

Having thus described my invention, what I claim is:—

A clothes pounder comprising a hollow conical head having a plurality of members located therewithin and spaced from each other and having angularly-disposed walls secured to the head, a soap tray located within the head at the upper ends of said members, means forming a pivotal mounting for the tray and serving also to hold the tray against the head and in an active supporting position, the sides and ends of the tray being spaced from the inner walls of the head.

In testimony whereof I affix my signature in presence of two witnesses.

WALTER E. KEMP.
